TOBACCO SPREADER FOR ROD CIGARETTE
MAKING MACHINESAlbert Werner, Dresden-A, Germany, assignor to
"Universelle" Cigarettenmaschinen-Fabrik J.
C. Muller & Co., Dresden, GermanyApplication November 10, 1932, Serial No. 642,115
In Germany September 14, 1932

5 Claims. (Cl. 131—39)

In tobacco spreaders for rod cigarette making machines, it has already been proposed to impart to the tobacco descending through the delivery hopper into the rod trough a movement 5 in the direction of feed of the rod, *inter alia* by arranging compressed air nozzles on the walls of the delivery hopper, the said nozzles opening into the hopper and being set in the direction of feed of the rod. In the known type of such tobacco 10 spreaders, the compressed air nozzles extend almost over the full height of the hopper. Consequently, the tobacco is under the influence of the compressed air for a relatively large distance of fall, resulting in the production of eddies in the 15 delivery hopper which occasionally prevents a uniform descent of the tobacco.

It is the object of the present invention to obviate this disadvantage. For this purpose, according to the invention, the compressed air nozzles for supplying air are arranged only at the lower end of the delivery hopper. The air is thus introduced into the chamber uniformly in all points, so that it is impossible for larger or smaller air velocities or eddies to be set up any- 25 where.

In order to prevent air entering the tobacco channel and acting upon the tobacco situated there while the machine is stopped, provision is made at the same time for the compressed air to 30 be shut off when the machine is stopped.

A constructional example of the invention is shown in the accompanying drawing, wherein:

Figure 1 is a front elevation of the tobacco spreader with the adjoining delivery channel.

Figure 2 is a plan of Figure 1 partly in section.

Figure 3 is a diagrammatic side elevation of the device, and

Figure 4 is a section through the lower part of the delivery hopper on a larger scale.

The tobacco fleece is supplied by a conveyor belt *a* which runs over a roller *b*. The tobacco falls off the conveyor belt *a* into the hopper *c* which opens into the rod trough. In the constructional example shown, the said rod trough is

a suitable gap and on which is mounted the hopper formed of two parts *e* and *f*, between which is left a gap, as will be seen more particularly in Figure 4. The two parts *e* and *f* are constructed in the

form of hollow bodies and are closed outwardly by cover plates *g* and *h*, respectively. The part *f* is secured by two hinges *i* to the machine frame, so that it can be turned forwardly about the pins *i* of the said hinges for rendering the interior of the hopper accessible. The lower closure member of the rod trough is constituted by a con-

veyor belt or a paper strip *k* which in known manner is carried over a roller *k*¹. The finished rod is shown at *m* in Figure 1. The cavities formed in the lateral walls of the rod trough *e* and *f* are connected by supply pipes *n* and *n*¹, respectively, to a compressed air conduit *o*. In addition, the inwardly directed walls of the parts *e* and *f* are provided with bores *p* which, as shown in Figures 2 and 4, pass through the walls horizontally but obliquely in the direction of feed of the rod. A throttle valve *q*, provided in the compressed air supply conduit *o*, is rotatable about a spindle *q*¹ and is connected by a pull rod *r* to the stopping device for the machine in a manner not shown in the drawing so that, on stopping the machine, the throttle valve is brought into the closed position shown in the drawing, while it is opened on starting the machine. Since the front wall of the tobacco channel *f* is adapted to turn about the hinge pins *i*¹, the air conduit *n*¹ of course must also be hinged. For this reason, the conduit will preferably be made in the form of a movable pipe.

The holes *p* do not extend over the entire length of the channel, but, as shown in Figure 1, the part situated towards the outlet end is free from such bores. In order to prevent the air from being obstructed at the outlet end of the tobacco channel and flowing upward and consequently deflecting the descending tobacco from its proper direction, the walls of the tobacco funnel at this end are not made vertical in the usual manner, but, on the contrary, a sloping part *s* adjoins the vertical lateral wall. The said part slopes downward in the direction of the tobacco rod.

Of course, the manner of carrying out the invention may be different in its constructional details.

In other respects, the operation of the device is known. The tobacco first descends through the hopper *c* in the usual manner, and as soon as it enters the tobacco channel it is deflected into the feed direction by the currents of compressed air entering therein. The compressed air acts upon the tobacco only while the machine is running, and on the machine being stopped, the compressed air is shut off.

I claim:—

1. A tobacco spreader for cigarette rod machines, comprising a delivery hopper for the tobacco having imperforate walls, a rod trough on the lower end of the hopper, and compressed air means including a plurality of air nozzles solely in said trough to impart thereby a movement of the tobacco in the trough in the direction of feed

of the rod and to prevent eddy currents in the delivery hopper.

2. A tobacco spreader according to claim 1, said plurality of air nozzles being provided in the trough along a certain distance thereof, and the remaining length of the trough at the outlet end thereof being free of any nozzles.

3. A tobacco spreader according to claim 1, in which at least a part of an end wall of the delivery hopper, at the outlet end of the tobacco trough, slopes downwardly in the direction of the cigarette rod.

4. A tobacco spreader according to claim 1, said trough consisting of two walls in the form

of hollow bodies having the hollow portions as a part of the compressed air means and said walls having the air nozzles therein for the passage of compressed air.

5. A device for spreading tobacco on a paper strip, comprising a delivery hopper for the tobacco having imperforate walls, and means interposed between the hopper and the strip and including a plurality of air nozzles to impart a movement of the tobacco in said means in the direction of feed of the strip to prevent eddy currents in the delivery hopper. 5 10

ALBERT WERNER.
